Robert S. Phillips

ATTORNEY

UNITED STATES PATENT OFFICE.

ERNEST LEONARD FORD, OF DARLINGTON, ENGLAND.

VENTILATOR OF THE EJECTOR TYPE.

Application filed October 25, 1924. Serial No. 745,915.

To all whom it may concern:

Be it known that I, ERNEST LEONARD FORD, a subject of the King of Great Britain and Ireland, residing at Honeypot 5 Works, Honeypot Lane, Darlington, in the county of Durham, England, have invented certain new and useful Improvements in Ventilators of the Ejector Type, of which the following is a specification.

This invention relates to ventilators of the ejector type for closed compartments such as the bodies of vehicles, and it has for its object a construction which is highly efficient at all speeds at which the vehicle 10 may be moving, which has no moving or loose parts liable to get out of order or lost, and which has a presentable appearance.

I attain these ends by the construction shown in the accompanying drawings in 20 which:—

Figures 1, 2 and 3 are views in side elevation, end elevation and plan respectively, and

Figure 4 is a view in longitudinal section 25 on line $v v$ Figure 3.

Throughout the views similar parts are marked with like numerals of reference.

The hollow chamber 1 is of lozenge or 30 rhomb shape and has both its sides 2 and its top 3 of convex form and in each of the sides 2 are two apertures 4 and 5 the apertures 4 being approximately to one end of the chamber and those 5 being approximately to the other end thereof. These apertures are of approximately V-shape with 35 their apices towards the ends of the chamber. On each side of the chamber are two exterior plates forming deflectors 6 and 7 which are preferably inclined or curved so as to coincide or register with the edges of the apertures nearest to the ends of the body. The deflectors of each pair of apertures 4, 4 and 5, 5 are extended across the 40 interior of the body 1 to form interior deflectors 8 and 9 and at the bottom of each of said interior deflectors at its centre is formed a V-shaped projection 10 the apex of which points towards the centre of the chamber. In the plate which forms the base 45 11 of the interior of the chamber is a narrow centrally arranged transverse aperture 12 and said base slopes upwards from each end of the chamber towards said aperture 50 and terminates at said aperture in upwardly curved lips 13. On the interior

walls of the sides 2 of the chamber 1 at the centre thereof are projections 14 which operate to restrict the width of the interior of the chamber at the aperture 12. At the tops of the deflectors or vanes 6 and 7 are horizontally or approximately horizontally disposed plates 15 which extend towards the centre of the chamber and preferably taper towards said point and which may be provided with openings 16 which intensify the negative pressure at the apertures 4 or 5 by reason of the flow of air over said openings.

The action of the ventilator is as follows:—

Directly the vehicle is in motion and so long as it continues to move at a slow speed a current of air strikes the front pair of deflectors—say 6 and 6—and is deflected by them over the front pair of apertures 4 and 4 thus setting up a negative pressure or partial vacuum at said apertures. This negative pressure creates a similar negative pressure in the interior of the chamber 1 which causes a suction action at the central aperture 12 in its base thereby extracting the air out of the body of the vehicle through the hole in the roof with which said aperture registers. The current of air after passing the front pair of deflectors 6 and 6 flows inwardly towards the sides 2 and is caught by the rear pair of deflectors 7 and 7 and is deflected into the interior of the chamber through the rear apertures 5 and 5 at an increased positive pressure 50 which flowing forward over the aperture 12 augments the negative pressure in the front part of the chamber and so assists to increase the suction effect at the central aperture 12. This suction effect is maintained even at extremely low speeds by reason of the restriction of the width of the chamber at its central part by the projections 14 and 14, the upward slope of the base 11 of the chamber, the upturned lips 13 of said base at the edges of the central aperture and the curvature of the top 3 of the chamber 1. When higher speeds are attained the area of negative pressure set up by the front pair of deflectors is considerably increased and extends completely around the outside of the chamber so that a negative pressure is set up at the rear apertures as well as at the front ones whereby a negative pressure or partial vacuum is produced at 100 105 110

both ends of the chamber. When a side or three-quarter wind is blowing, the deflectors opposite to those facing the wind set up the necessary suction effect and in the case of 5 a following wind which is blowing at a greater speed than the vehicle is travelling the action is exactly the same only reversed.

I wish it to be clearly understood that I 10 may use any number of apertures 4 and 5 on each side of the chamber 1 and at each end thereof and that the deflectors coacting with said apertures may be set at any suitable angle both with the base and side walls of said chamber. Further I do not 15 limit myself to the use of a single suction aperture in the interior of the chamber.

What I claim is:—

1. A ventilator of the ejector type comprising a chamber which consists of a base 20 having a transversely arranged opening at the centre of its length, a top, and a pair of forward and rearward converging side walls having openings located in opposed pairs near the ends of the chamber, and 25 plates forming exterior deflectors on the side walls of said chamber adjacent to said side openings.

2. A ventilator of the ejector type comprising a chamber which consists of a base 30 having a centrally arranged transverse opening, a top, and side walls which converge towards the ends of the chamber and have openings located in opposed pairs near the ends of the chamber, and inclined plates 35 forming exterior deflectors on the side walls of the chamber which register with the forward edges of the side openings therein.

3. A ventilator of the ejector type comprising a chamber consisting of a base having a centrally arranged transverse opening, a top, side walls connecting said base and said top and which converge towards each end of the chamber and in which are 45 pairs of angularly shaped openings which are located in opposed pairs near the ends of the chamber, inclined plates on the side walls of said chamber adjacent to said side openings which form exterior deflectors, and interior deflectors at each end of the 50 chamber.

4. A ventilator of the ejector type comprising a chamber which consists of a base having a transverse and centrally arranged opening and which slopes upwardly towards the centre of its length, a top, and side walls between said base and said top each having a pair of V-shaped openings located near the ends of said chamber the apex of each opening being towards one end 55 of the chamber, inclined plates forming exterior deflectors on the side walls of said chamber which register with the upper edges of said V-shaped openings, interior deflectors at each end of the chamber which 60 coact with the exterior deflectors, and pro-

jections on the interior side walls of the chamber which operate to restrict its width at the opening in its base.

5. An exhaust ventilator the width of which tapers from its centre to each end 70 comprising a base which slopes upwardly towards the centre of its length and has a transverse centrally arranged opening, a top, and side walls between said base and said top, said side walls having V-shaped 75 openings located in opposed pairs near the ends of the apparatus each with its apex towards the adjacent end of the apparatus, inclined plates forming exterior deflectors on the side walls of said apparatus which register with the upper edges of said side openings, interior deflectors which extend across the interior of the apparatus at each end thereof and coact with the exterior deflectors, V-shaped projections at the center of 80 each interior deflector the apex of each of which points towards the centre of the apparatus, and projections on the interior side walls of the apparatus which operate to restrict its width at the central opening in its 85 base.

6. An exhaust ventilator the width of which tapers from the centre towards each end comprising a top which is of convex 95 form, a base which slopes upwardly towards the centre of its length, and has a transverse centrally arranged opening, and two side walls which converge towards the ends of the apparatus and have V-shaped 100 openings located in opposed pairs near the ends of the apparatus each with its apex towards the adjacent end of the apparatus, inclined plates forming exterior deflectors on the side walls of said apparatus which register with the upper edges of said side 105 openings, interior deflectors lying within and across each end of the apparatus which coact with the exterior deflectors, V-shaped projections at the centre of each interior deflector the apex of each of which points towards the centre of the apparatus and projections on the interior side walls of the apparatus which operate to restrict its width 110 at the opening in its base.

7. An exhaust ventilator the width of 115 which tapers from its centre towards each end comprising a base which slopes upwardly towards the centre of its length, and has an opening at said centre, a top located above said base and two side walls which 120 converge towards the ends of the apparatus and have V-shaped openings located in opposed pairs near the ends of the apparatus each with its apex towards the adjacent end of the apparatus, inclined plates forming 125 exterior deflectors on the side walls of said apparatus which register with the upper edges of said side openings, interior deflectors which lie within and across each end 130 of the apparatus and coact with the exterior

deflectors, V-shaped projections at the centre of each interior deflector the apex of each of which points towards the centre of the apparatus, horizontally disposed apertured extensions of the exterior deflectors, and projections on the interior side walls of the apparatus which operate to restrict its width at the opening in its base.

8. A double-ended symmetrical exhaust 10 ventilator comprising a base having a narrow centrally located opening, a roof above said base, a pair of forward and a pair of rearward converging side walls between said base and said roof having openings communicating with the interior of the ventilator, a pair of forwardly and a pair of rearwardly inclined plates on the exterior of the side walls fore and aft respectively of the openings in said side walls, and an interior 15 wall at each end of the ventilator lying between the forward edges of each pair of openings in the side walls and extending from the base to the roof.

9. A double-ended symmetrical exhaust 20 ventilator comprising a base having a narrow centrally located opening, a roof above said base, a pair of forward and a pair of rearward converging side walls between said base and said roof having openings communicating with the interior of the ventilator, a pair of forwardly and a pair of rearwardly inclined plates on the exterior of the side 25 walls fore and aft respectively of the openings in said side walls, and an interior wall at each end of the ventilator lying between the forward edges of each pair of openings in the side walls and extending from the base to the roof.

side walls fore and aft respectively of the openings in said side walls, an interior wall at each end of the ventilator lying between 35 the forward edges of each pair of openings in the side walls and extending from the base to the roof, and interior transverse projections on the side walls restricting the centrally arranged opening in the base.

10. A double-ended symmetrical exhaust 40 ventilator comprising a base sloping upwardly towards the centre of its length and having a narrow transversely arranged opening at said centre, a top above said base, a pair of forwardly and a pair of rearward converging side walls between said base and said top, having openings communicating with the interior of the ventilator, a pair of forwardly and a pair of rearwardly inclined 45 plates located on the exterior of the side walls in alignment with the forward edges of the openings in said side walls, horizontally disposed extensions of said inclined plates at the upper edges of same, an interior wall at each end of the ventilator lying between the forward edges of each pair of openings in the side walls and extending from the base to the top, and interior 50 transverse projections on the side 55 walls restricting the centrally arranged opening in the base.

ERNEST LEONARD FORD.
